UNITED STATES PATENT OFFICE.

JOHN P. NICHOLS, OF MARION, INDIANA.

EXERCISING-MACHINE.

SPECIFICATION forming part of Letters Patent No. 408,251, dated August 6, 1889.

Application filed April 27, 1889. Serial No. 308,807. (No model.)

To all whom it may concern:

Be it known that I, JOHN P. NICHOLS, a citizen of the United States, residing at Marion, in the county of Grant and State of Indiana, 5 have invented a new and useful Exercising-Machine, of which the following is a specification.

This invention has relation to exercising-machines for use in gymnasiums and other 10 places, and among the objects in view are to provide a machine adapted to be struck either by the hand, base-ball bat, or other bludgeon, or with a ball, which machine is so constructed as to register the amount of force given.

15 The invention consists in certain features of construction hereinafter specified, and more particularly pointed out in the claims.

Referring to the drawings, Figure 1 is a perspective of a machine constructed in accordance with my invention. Fig. 2 is a rear view.

Like numerals of reference indicate like parts in both the figures.

1 represents a suitable base or sill. The 25 same consists of a longitudinal central piece 2 and transverse end pieces 3 and 4. Upon the rear piece 4 are mounted opposite uprights 5, having a transverse superimposed bar 6. At the front portion of the base, and 30 in this instance upon a cross-piece 3, are mounted opposite standards 7, having bearings 8, and in the same is journaled a rock-shaft 9, from the center of which projects upwardly a rock-arm 10, carrying near its upper 35 end and upon its front face a blow-receiving abutment 11, formed with oppositely-inclined guide-arms 12, and provided intermediate the same with a fabric or other noise-deadening buffer 13. Extending from near the lower 40 end of the rock-arm 10 is a horizontal rock-arm 14, which is braced by means of diagonal braces 15, extending from the upper end of the arm 10 to near the rear end of the arm 14, said arm 14 projecting rearwardly beyond the 45 cross-piece 4 of the base.

Upon standards 16, projecting oppositely from the rear cross-piece 4, is mounted a casing 17, the front face of which is provided with a dial 18, and through the same is passed 50 a transverse shaft 19, carrying at its outer end a movable pointer 20 and within the casing a gear-wheel 21.

To one side of the shaft 19 and in suitable bearings 22, formed in the front and rear walls of the casing, there is journaled an oscillating shaft 23, provided with a toothed sector 24, the teeth of which are designed to mesh with the gear-teeth 21. Upon the inner face of the sector is provided a ratchet 25, into which is designed to mesh a spring-pressed pawl 26, normally thrown into the path of the ratchet by means of a spring 27. The end of the pawl is projected from the side of the casing to an opening and adapted to be thrown by hand or otherwise into or out of connection with the teeth of the ratchet. A coiled spring 28 connects one end of the sector 24 with the roof of the casing and serves to maintain said sector in a raised position, or to that degree in which the movable pointer 20 registers at zero.

Upon the longitudinal base 2, I mount in this instance an elliptic spring 29, the upper portion of which takes under the rock-arm 14 and serves to return the same to position after having been depressed, as herein-after described.

30 represents a connecting-rod, which is pivoted to the inner end of the sector 24, and which is provided with a lower slotted portion 31, which receives a laterally-projecting pin 32, projecting from the side of the rock-arm 14. Suitable side braces 33 project from the standards 16 to the standards 7.

If desired, I may mount the casings 17 directly upon the transverse bar 6; but in order to avoid transferring the shock to the casing and its mechanism I prefer to mount the same upon separate standards 16. Between the lower face of the transverse bar 6 and the upper face of the rock-arm 14, I mount a rubber or other noise-deadening buffer 34.

The operation of my invention is as follows: By striking between the guide-arms 12 either with a hammer, bat, ball, or by hand, the rock-arm 10 is tilted to the rear, as is also the rock-shaft 9, and the rock-arm 14 depressed, all to a degree in accordance with the force of the blow given. As the rock-arm 14 descends or is depressed, it, by means 100 of the connecting-rod 30, oscillates the sector 24, which, being in mesh with the gear 21, rotates the same and its shaft 19, which carries the movable pointer 20 over the face of the

dial in accordance with the amount of rotation given its shaft. The spring 29 returns the rock-arms 14 and 10 to their normal position, leaving the dial at the point to which it is brought, in which position it is held by means of the sector 24, said sector being held by the spring-pressed pawl 26. The return of the rock-arm 14 is permissible without changing the position of the pointer and its mechanism by reason of the slot 31 in the connecting-rod 30. After inspecting the dial, by simply depressing the rear end of the pawl 26, the same is withdrawn from mesh with the ratchet 25, and the sector resumes its normal position, and in so doing brings the pointer back to the zero-point.

A coiled spring 36 is connected at its lower end to the end of the rock-arm 14 and at its upper end to the casing, the same aiding to return the rock-arm after having been depressed. This spring, however, is not necessary.

Having described my invention, what I claim is—

1. An exercising-machine for receiving blows, comprising a base, a blow-receiving rock-arm mounted on a rock-shaft journaled on the base, a rearwardly-extending rock-arm, a movable pointer mounted over a dial, and devices connecting the arm and pointer and adapted to rotate the latter by the oscillation of the former, substantially as specified.

2. An exercising-machine for receiving blows, comprising a base, a depressible rock-arm, a dial-case mounted above the rock-arm and carrying a movable pointer, a sector mounted in the case and adapted to mesh with a toothed wheel mounted on the dial-shaft, and a rod connecting the sector and the rock-shaft, substantially as specified.

3. In an exercising-machine, the combination, with a base provided at its forward end with a rock-shaft carrying an upwardly-projecting blow-receiving rock-arm and a rearward rock-arm, of a dial-case mounted above the rock-arm and provided with a pointer-shaft carrying a gear, a sector mounted at one side of the gear and meshing therewith, and a loosely-pivoted connecting-rod connecting the inner end of the sector with a pin projecting from the rock-arm, substantially as specified.

4. In an exercising-machine, the combination, with blow receiving and transmitting mechanism, of blow-registering mechanism connected therewith and independent means for returning each to its normal position irrespective of the movement of the other, substantially as specified.

5. In an exercising-machine, a base provided at its forward end with a rock-shaft having upwardly-projecting and rearwardly-projecting rock-arms suitably braced, and a spring for returning the rear rock-arm to position, in combination with a dial-case mounted above the rearwardly-projecting rock-arm and provided with a pointer-shaft having a gear, a sector mounted to the side of the gear and meshing therewith, a spring for returning the sector to its normal position, a ratchet-plate mounted on the sector, and a pawl for engaging the teeth of the ratchet, substantially as specified.

6. The base-sills 2, 3, and 4, arranged as described, in combination with the standards 7, 75 mounted upon the sill 3 and provided with bearings 8, carrying a rock-shaft 9, and the rock-arms 10 and 14, the former provided with the blow-receiving device 11, having opposite guide-arms 12 and buffer 13, and the spring 29, mounted on the sill 2 and under the rear end of the rock-arm 14, substantially as specified.

7. The combination, with the base having the rock-shaft 9 and arms 10 and 14, the former provided with the blow-receiving device and the latter having the spring 29, of the supports 5, having the cross-bar 6 and buffer, and the standard 16, having the casing 17, provided with the dial 18, transverse dial-shaft 19, carrying the dial 20 and gear 21, and the sector-shaft 23, mounted in bearings 22, carrying the sector 24, meshing with the gear and having the return-spring 28 and ratchet-plate 25, and the spring-pressed pawls 26, substantially as specified.

In testimony that I claim the foregoing as my own I have hereto affixed my signature in presence of two witnesses.

JOHN P. NICHOLS.
